CLAIM

The ornamental design for a motorcycle fairing, as shown and described.

DESCRIPTION

FIG. 1 is a front elevation view of a motorcycle fairing showing the new design;

FIG. 2 is a rear elevation view thereof;

FIG. 3 is a left side elevation view thereof;

FIG. 4 is a right side elevation view thereof;

FIG. 5 is a top plan view thereof.

The fragmentary broken line representations of portions of a motorcycle in FIGS. 3, and 4, illustrate the environment in which the fairing is used but form no part of my design.
